Patented July 16, 1918.

UNITED STATES PATENT OFFICE.

CHARLES F. RABENOLD, OF GLENSIDE, AND GEORGE W. CARNS, OF PHILADELPHIA, PENNSYLVANIA.

LAMP.

1,272,524.

Specification of Letters Patent. Patented July 16, 1918.

Application filed September 17, 1917. Serial No. 191,866.

To all whom it may concern:

Be it known that we, CHARLES F. RABENOLD and GEORGE W. CARNS, citizens of the United States, residing at Glenside, in the 5 county of Montgomery and State of Pennsylvania, and Philadelphia, county of Philadelphia, and State of Pennsylvania, have invented certain new and useful Improvements in Lamps, of which the following is 10 a specification.

One object of our invention is to provide a single lamp for use on automobiles and which will take the place of the two head lights as commonly used.

15 Another object is to include in our improved lamp, an elongated casing to provide a general illumination, the construction being such that the light rays reflected therefrom will normally be projected straight 20 ahead of the vehicle and toward the ground.

A further object is to provide an adjustable light-reflecting element which can also be employed as a blind.

A still further object is to so construct our 25 invention that it can be manufactured and sold at a reasonably low cost.

These objects, and other advantageous ends which will be described hereinafter, we obtain in the following manner, reference 30 being had to the accompanying drawings in which—

Figure 1 is a front elevation of our improved lamp.

Fig. 2 is an enlarged section taken on the 35 line 2—2 of Fig. 1.

Fig. 3 is a section taken on the line 3—3 of Fig. 2, the length of the casing being foreshortened.

Fig. 4 is a sectional plan view of our invention showing a slight modification of the reflectors.

Referring to Figs. 1 to 3 inclusive, 1 is an elongated casing having an opening 2 at the front, closed by a glass 3. This casing 45 is preferably made of sheet metal and has closed end sections 4 and a curved back 5. The top 6 of the casing includes a portion 7 which slants downwardly in a forward direction and overhangs the bottom 8 of the casing. The glass 3 slants rearwardly from the front edge of the portion 7 to the front

edge of the bottom 8 as clearly shown in Fig. 2.

A plurality of electric bulb sockets 9 are secured to the back 5 of the casing 1, and 55 these sockets are designed to receive electric bulbs or lamps 10, there being four bulbs and four sockets illustrated in the accompanying drawings positioned within the length of the casing as illustrated in Fig. 1. 60

The electric bulbs 10 as illustrated, are positioned substantially midway between the top 6 and bottom 8 of the casing 1. A reflector 11 is positioned within the casing 1 and has a section 12 located immediately in 65 the rear of the bulbs 10, said section slanting forwardly as clearly shown in Fig. 2.

Another section 13 of the reflector 11 is positioned above the bulbs 10 and at an incline. As illustrated, no portion of the reflector 11 projects below the level of the 70 electric bulbs 10 so that the direct light of the lamps 10 is projected on the sections 12 and 13 of the reflector 11 and reflected downwardly.

75 The reflector 11 extends the full length of the casing 1 (see Fig. 3). A plate 14 extends substantially the full length of the casing 1 and is secured to a rock shaft 15 which is journaled within the casing 1 and has a 80 crank arm 16 at one end thereof to which is connected a rod 17.

The plate 14 serves as a combined light deflector and blind and has a reflecting surface 18 which when moved into the full line 85 position shown in Fig. 2, serves to deflect the rays of light from the bulbs 10 in a downward direction as shown by the dotted line 19. Furthermore, this reflecting surface 18, when the plate 14 is in the position 90 illustrated in full lines in Fig. 2, serves to reflect downwardly rays of light which first engage the reflector 11 such for example as illustrated by the dotted lines 20.

When the plate 14 is moved into the position shown at 21 by dot-and-dash lines in Fig. 3, it serves as a blind for the light in the upper part of the casing, and thereby reduces the amount of the reflected light and also a part of the direct light from the bulbs 100 10. The ends 4 of the casing are preferably provided with trunnions 22 so that the cas-

ing can be mounted within any suitable bearing and adjusted.

The plate 14 can be moved by actuating the rod 17, and this rod, if desired, can extend to the interior of the automobile.

In a lamp constructed as above described, the light can be made to be projected forwardly and at an angle downwardly toward the ground which is extremely desirable 10 when a lamp is used on an automobile.

In Fig. 4, we have illustrated a reflector 11^a which is substantially the same construction as the reflector 11 with the exception that it has end portions 23 which flare 15 forwardly from the rear of the casing and therefore give a slight lateral distribution of the light rays. In all other respects the construction shown in Fig. 4 is similar to that above described, and we have therefore 20 given corresponding parts similar reference numerals.

While we have described our invention as taking a particular form, it will be understood that the various parts of our invention may be changed without departing 25 from the spirit thereof, and hence we do not limit ourselves to the precise construction set forth, but consider that we are at liberty to make such changes and alterations 30 as fairly come within the scope of the appended claims.

Having thus described our invention, what we claim as new and desire to secure by Letters Patent is:

35 1. An elongated lamp casing having an elongated opening in its front, the top and the bottom of said casing having portions adjacent said opening which taper forwardly with respect to each other and with 40 the upper surface of the casing slanting for-

wardly and downwardly, and a source of light within said casing positioned to the rear of said tapered portion, substantially as described.

2. A lamp casing having an opening in its 45 front, the top of said casing adjacent said opening having a portion slanting downwardly, a source of light within said casing, a reflector within said casing, and a movable plate positioned within said casing and having a portion adapted to be interposed between the top of said reflector and the portion of the casing providing the top of said opening, substantially as described.

3. A lamp casing having an opening in its 55 front, the top of said casing adjacent said opening having a portion slanting downwardly, a source of light within said casing, a reflector within said casing, and a movable plate positioned within said casing and having a portion adapted to be interposed between the top of said reflector and the portion of the casing providing the top of said opening, said plate having a rear light-reflecting surface for deflecting intercepted 65 rays from the source of light and from said first reflector back to said first reflector and thence out of that portion of the opening in the casing which is located below a horizontal plane including the bottom of said 70 plate, substantially as described.

In testimony whereof we have signed our names to this specification in the presence of two subscribing witnesses.

CHAS. F. RABENOLD.
GEORGE W. CARNS.
